UNITED STATES PATENT OFFICE.

NEWELL SANDERS, OF CHATTANOOGA, TENNESSEE.

DESIGN FOR A BASE FOR CANE-MILLS.

SPECIFICATION forming part of Design No. 27,626, dated September 7, 1897.

Application filed July 27, 1897. Serial No. 646,148. Term of patent 14 years.

To all whom it may concern:

Be it known that I, NEWELL SANDERS, a citizen of the United States, residing at Chattanooga, Tennessee, have invented and 5 produced a new and original Design for a Bed-Plate for Cane-Mills, of which the following is a specification.

In the accompanying drawings I have illustrated my design.

10 Figure 1 is a plan view; Fig. 2, a view of one side; Fig. 3, a view of the opposite side. Fig. 4 is a view of one end, and Fig. 5 a view of the opposite end.

As shown in the drawings, the leading feature of my design is the peculiar configuration of the base, as seen in side and end elevation. The base has two projecting columns, one near the rear end and the other parallel thereto, with a space between the columns, 15 as shown in Figs. 1 and 2, at one end thereof

this space extending into the solid base. As shown in the plan view, the end of the base opposite the columns is made with a depression with an inclined bottom and converging walls. An opening is formed in the front wall 25 in line with the depression, and this opening is provided with a discharge-spout, as shown.

In Fig. 4 the dotted lines show the shape of the space and the solid portion of the base in rear of the space. The other figures show the 30 configuration and shape of the base from each side end and in plan.

What I claim is—

The design for the base of a cane-mill as herein shown and described.

NEWELL SANDERS.
